UNITED STATES PATENT OFFICE.

RHOS ABIJAH DYKE, OF MYRTLE POINT, OREGON.

COMBINATION SQUARE AND BEVEL.

Application filed June 7, 1924. Serial No. 718,621.

This invention relates to mechanics' squares, especially to carpenters' squares and particularly to the latter with attachments for facilitating the laying out of angles and for solving mathematical problems relating thereto.

The objects of my invention are to provide a tool which will serve as a square and provide for laying out and scribing of any desired angle on timbers and other material in connection with carpentering or similar work and which will automatically indicate the length of the hypotenuse of any right angle triangle, the basis of all ordinary roofing problems in the joining of the timbers.

While my invention is not limited to the solving of roof frame problems since the instrument may be arbitrarily graduated to suit any particular class of work, its application to the framing of roofs appears to be the most useful, and therefore the graduations and examples given hereinafter refer to this usage.

Briefly stated my invention comprises a right angle triangle with a telescopic hypotenuse pivotally secured to one side of the triangle and slideable along the other, the sides and telescopic hypotenuse bearing cooperating or related series of graduations having certain relation to the problems to be solved.

The instrument may be of any size and the graduations proportionately spaced to suit, but a practical size for carpentering is about a foot in greatest length, though if made two feet long the graduations are further spaced and may be more easily read.

In the drawings, Figure 1 shows one side of my instrument, and Figure 2 the other side, while Figure 3 is an edge view of the telescopic hypotenuse or "fence" as such a hypotenuse is called when applied to a carpenter's square.

In further detail the instrument comprises a 90° square having a blade B, a tongue T and a "fence" F.

The fence is telescopic, and bifurcated at both ends to straddle both the tongue and the blade, and it is pivotally connected to the blade at a point A by a hinge the pivot of which is coincident with the upper edge of the blade in such a manner that the fence can fold down parallel to the blade as shown in dotted position in Figure 1.

The tongue is slotted at S and the free end of the fence is adjustable on the tongue

through engagement with a pin P extending through the slot and carried by a sliding block b. The center of the pin is coincident with the same edge of the fence which intersects the pivot A.

The fence telescopes by having a thinner portion which bears the graduations slide within the thicker lower blade straddling portion as shown. The tongue straddling portion is provided with a clamping screw 3 and a nut C whereby the fence may be clamped to any adjusted position along the tongue by turning the nut c upon the screw 3 which causes the sides of the bifurcated end to bind upon the tongue.

Several rows of graduations are shown along both sides of the tongue and fence. These graduations are for the solving of roof frame construction problems and are based on the common method of using 12 inches, 17 inches and 13 inches on the blade of a carpenter's steel square as respectively representing the run of common rafters, hip rafters, and octagon hip rafters and measuring the length from these points across the corner of the square to the proportionate rise of the roof on the tongue of the square to obtain the unit length for each foot of span of the roof for common, hip or octagon hip rafters respectively and also to determine their plumb and bevel cuts in connection with the frame construction of a 45° pitch roof.

My instrument, while using the same principle, automatically registers on the several scales G on the movable telescopic fence the unit lengths referred to above, and also in addition scales the difference in length of jack rafters, abutting hip or valley rafters at 12, 16 or 24 inch spacing.

By pivoting and centering the fence at A and P on its working edge as described, it allows the base of the triangle to remain permanently at a predetermined length since the moving center P while traveling along the slot in T is in a line perpendicular to its starting point, and thus indicates at any position of fence F with the aid of the proportionate scales on T and F the relative lengths of the three sides of a right angle triangle.

On the instrument, not drawn to scale the divisions (12) on T comprise a substantially one-half scale standing perpendicular to the base and distant from center A 12 inches of the same scale. Moving F to intersect the scale in column 12 on T at 12",

as shown in Figure 1, it is in position for marking a miter of 45° or the plumb and bevel cuts of rafters for a square pitched roof.

5 At the same time on a scale exposed on the extended fence at the point where it pulls out will be found the extended length between centers A, P on F, or the length of a common rafter per foot of run. In 10 other columns G will be found indicated the difference in length of jack rafters spaced 16" or 24" apart.

15 Scale 17 on tongue T represents a distance of seventeen inches from center A. Moving the fence F to 12 in column 17 the blade gives the bevel cut of hip rafter and the tongue the plumb cut. In the column nearest the inner side on F the length of hip rafters for one foot of run is automatically registered 20 by the mark of the scale nearest to the inner edge of the blade straddling portion of the fence F.

25 In the case of common and hip rafters it remains only to multiply the unit length registered on the scale by the run of roof, i. e. half the width of building, to find the total length of rafters.

30 In the column on T for "hip side cut on tongue" this is the bevel required to fit a hip rafter against the ridge board, or opposite hip rafter, and the scale indicates one inch rise per foot between each division.

35 In the column for "jack rafters side cut on blade", the bevel formed by F and B fits the jack rafters sideways against hip or valley rafters (the ordinary plumb cut of common rafters is used for the up and down cut). The side cut, invariably so called, is marked on the edge of the rafter.

40 On the reverse side of the instrument, Figure 2 there is a column for common rafter rise, giving plumb and bevel cuts, also the length on fence, and in other columns giving the lengths of octagon hip

rafters, and the difference in length of octagon jack rafters at 12 and 16 inch centers, for 24 inch centers the 12 inch readings are doubled.

45 It will be apparent from what has been shown that scales different from those shown may be provided, and it should be noted that the fence being thicker than the blade and tongue may be placed against the timber from either side in scribing.

50 I am aware of the use of a graduated fence in connection with the common steel square for similar usage, but I do not know of such a fence being permanently pivoted to a square providing a definite base and being made telescopic with several columns 60 of proportionate figures thereon bearing a relation to proportionate scales along the tongue.

55 I claim:

1. A combination square having two legs 65 forming a right angle, an extendible fence pivoted at one end to the free end of the first leg and with the other end engaging the second leg and being slideable therealong, there being a line of graduations along the 70 second leg having proportionate relation to roof timber rises, the distance from said line of graduations to the pivotal point taken along the first leg having the same proportionate relation to the roof timber 75 runs, and the extendible fence having graduations registering in similar terms quantities depending upon the angular relation of the fence to the legs.

2. A combination square having two legs 80 forming a right angle and one of said legs having a slot, an extendible fence pivotally connected at one end to the free end of the unslotted leg, a block slideable in the slot of the other leg and having means bearing 85 upon the free end portion of said fence.

RHOS ABIJAH DYKE.
